AIR RELEASE APPARATUS

Waldo P. Schirmer, Cleveland, and Richard A. Knaus, Shaker Heights, Ohio, assignors, by mesne assignments, to Symington-Wayne Corporation, Salisbury, Md., a corporation of Maryland

Application October 5, 1953, Serial No. 383,995

2 Claims. (Cl. 137—171)

This invention relates to air, vapor or gas releases and priming devices for pumps in closed discharge system, the most important object of the invention being to provide an air release for an air accumulator which removes the air from a fluid system quickly and positively upon each operation of the pump.

Another object of this invention is to provide an air release capable of removing small quantities of air continuously while discharging a minimum of fluid.

A further object of the invention is to provide an air release having a relatively large vent operable only when large quantities of air are to be removed and a small vent capable of removing air in amounts insufficient to cause operation of the large vent, to avoid recirculating large quantities of liquid.

Another object of the invention is to provide an air release capable of quickly disposing of air in large amounts without imposing a back pressure on the discharge portion of the system.

Other objects and advantages more or less ancillary to the foregoing, and the manner in which all the various objects are realized, will appear in the following description, which considered in connection with the accompanying drawings, sets forth the preferred embodiment of the invention.

In the drawings:

Fig. 1 is an elevational view of the preferred embodiment of my invention as it is used with a hydraulic supply system which is shown diagrammatically.

The air release is used to remove accumulated air and gases from a hydraulic system to facilitate the priming of the pump. Also, in the use of a meter for measuring quantities of fluid, it is essential that the liquid passing therethrough be free from entrapped air or gas if an accurate measurement is to be made. If the system is started and stopped frequently, a small amount of air leakage would render the measurements inaccurate on each operation and would render the system impractical for many purposes, such as a proportioning system.

To accomplish the rapid and continuous air elimination necessary to ensure the proper operation of a hydraulic system, we have provided an air release having a chamber 10 with a cover 12 removably fixed thereto, the cover 12 forming the upper portion of the chamber 10. A dome 14 is formed in the cover 12 to provide an air pocket for accumulating the air as the fluid rises in the chamber 10.

An inlet port 16 is formed in the wall of the chamber 10 adjacent to the top thereof and is of a size which will accommodate the fluid flow from the supply system. An outlet port 18 is provided in the lower portion of the chamber 10.

A valve having a seat 20 is in register with the outlet port 18. A valve member 22 is shiftable to a closing position in engagement with the seat 20 and is actuated by a float 24 mounted on an arm 26 pivoted to a stand 28. As the float 24 rises, as a result of a rise in the liquid in the chamber 10, the valve member 22 is moved

2

toward the closed position and further discharge of fluid is prevented. The discharge area of the valve is somewhat smaller than the area of the inlet 16 and consequently the discharge of liquid from the chamber is at a lower rate than the input thereof.

A second outlet port 30 is located in the lower portion of the chamber 10 and has a vertical conduit 32 connected therewith. The conduit 32 extends to the top portion of the chamber 10 and has its upper end terminated within the dome 14 and spaced slightly from the upper wall of the chamber 10. An orifice 34 is formed in the outlet 30 and is of a cross-section less than the cross-section of outlet port 18. A second orifice 36 is provided in the side wall of the conduit 32 near the lower end thereof. The orifice 36 has a smaller flow capacity than the orifice 34.

The air release may be used in a hydraulic system included herein diagrammatically as an example. A pump 38 has a suction line 40 connected to a source of liquid supply to be pumped; the suction line 40 having the usual foot valve located at the end thereof. A check valve 44 is located in the pump discharge line 46 intermediate the pump 38 and a metering device (not shown). A connection 48 is made between the pump discharge and the inlet port 16 of the air release for the passage of air and fluid thereto. The operation of the system would be enhanced in some instances by the inclusion of an air separator in the pump discharge line 46 with the air vent connection being made to the air release. A return line 50 connects the outlet ports 18 and 30 to a float chamber 52 which is vented to the atmosphere by the vent 54. A float valve 56 allows the return of fluid from the chamber 52 to the suction line 40 by way of a connection 58 therebetween. If the source of supply is vented to the atmosphere and remains at atmospheric pressure, the return line 50 may be connected thereto thus allowing the air release to discharge directly to the source of supply.

If the foot valve is leaky, the suction line 40 will fill with air or vapor which must be removed from the system before fluid flow of fluid is obtained. With the chamber 10 empty of fluid, the float 24 is in a lower position and the interior of the chamber 10 is open to the return line 50. In this condition, the air release is at atmospheric pressure and is vented to the atmosphere in order that the air and vapor in the pumping system may pass therethrough. On starting the pump, the air is discharged into the chamber 10 since a column of liquid would be resting on the check valve 44 and would prevent the entrance of air therein. Air entering the chamber will be immediately discharged and no appreciable pressure will be built up therein. It is noted that the pump will be primed with each since the discharge of the pump is maintained at atmospheric pressure and it is not necessary to prime against an increase in pressure as in the usual case.

When the air has been pushed out of the system by the presence of liquid, the fluid will enter the inlet 16 and due to the restriction of the flow from the outlet, the chamber 10 will begin to fill. However, due to the location of the conduit 32, air from the upper portion of the chamber 10 will be continuously exhausted, allowing the chamber to continue to fill and the fluid to raise the float 24 and close the outlet 18.

With the outlet 18 closed, the chamber 10 continues to fill as the air is released from the top of the chamber 10 through the orifice 34. When the liquid has reached the level of the top of the conduit 32, the flow therethrough continues at a rate as regulated by the size of the orifice 34. The diameter of the orifice 34 is not limited to any particular size since the requirements of different systems and different pump capacities may alter the de-

sirable characteristics of the flow therethrough. However, it is essential that the orifice 34 be larger than orifice 36 so that it will handle the flow of fluid from orifice 36 and the accumulated air.

When the pump 38 is shut down and air accumulates in the chamber 10, fluid therein may discharge through the small orifice 36 on the side of the conduit 32 and through the orifice 34 to the discharge line 50. When sufficient air enters the chamber 10 to lower the level of fluid to a point where the float 24 begins to fall, the contents of the chamber 10 is immediately discharged to the chamber 52. The air release then is immediately ready to handle large quantities of air and effect immediate removal thereof from the system.

It is noted that if all of the valves in the hydraulic system are tight and there is no leakage of air, the chamber 10, upon stopping the pump 38, will not empty since the lowering of the level of fluid therein would produce a vacuum which would prevent further flow therefrom. The device functions only in the event there is air to be eliminated. With the self-dumping feature, the device can never become air bound or inoperative since the presence of air in the smallest quantities immediately opens the passages which allows the air to be discharged without restriction.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

What is claimed is:

1. An air release apparatus comprising a closed chamber, an inlet port located in the upper portion of said chamber, a first outlet port located in the lower portion of said chamber, the cross-section of said first outlet port being smaller than the cross-section of said inlet port, a float valve operative to close said first outlet port when fluid in said chamber reaches a predetermined level, a second outlet port located in the lower part of said chamber having a cross-section smaller than that of said first outlet port, a vertical conduit within said chamber having its lower end surrounding said second outlet port and its upper end extending to a point adjacent the uppermost portion of said chamber, and an orifice in the side wall of said conduit in the lower portion of said chamber, said orifice having a cross-section smaller than that of said second outlet port.

2. An air release apparatus as defined in claim 1, wherein the combined cross-sections of the first and second outlet ports is no greater than the cross-section of the inlet port.
